LLOYD A. TUPPER, OF CHICAGO, ILLINOIS, ASSIGNOR TO CHICAGO MANIFOLD PRODUCTS COMPANY, OF CHICAGO, ILLINOIS, A PARTNERSHIP COMPOSED OF LLOYD A. TUPPER AND DAVID H. JONES

RIBBON GUIDE

Application filed November 16, 1931. Serial No. 575,354.

My invention relates to cylinders of multigraphing machines, and more particularly to the mounting of the ink-ribbons thereof, and has for its object to provide a simple attachment for holding and guiding the ribbon from lateral departure and crowding tendencies.

A further object of the invention is to so design the novel attachment that it does not interfere with the vital features or operation of the cylinder or the ribbon.

A still further object of the invention is to so design the novel attachment that it may be quickly mounted or removed without undue effort or skill.

With the above objects in view and any others that may suggest themselves from the specification and claims to follow, a better understanding of the invention may be had by reference to the accompanying drawing, in which

Fig. 1 is a front view of a typical multigraphing cylinder, showing my attachment in place;

Fig. 2 is a partial cross section, on an enlarged scale, taken on the line 2—2 of Fig. 1;

Fig. 3 is an edge view of one of the attachment units not in use;

Fig. 4 is a plan view of Fig. 3 on an enlarged scale, and medially broken away; and

Figs. 5, 6, and 7, are, respectively, sections on the lines 5—5, 6—6 and 7—7 of Fig. 4.

Referring specifically to the drawing, 10 denotes the shaft and 11 the ends of a typical multigraph cylinder, 12 indicating the part-cylindrical type form therefor, and 13 one pair of stay rods spacing the cylinder ends.

In multigraph cylinders, the ink-ribbon 14 leads from one spool over the type form and back to be wound on a companion spool, but as the travel of the ribbon in the zone of the spools is not pertinent to my invention, I have not shown the spools or those parts of the ribbon immediately in connection therewith. However, in passing over the form, the ribbon frequently has a tendency to shift sidewise whereby to crowd or wrinkle some of its portions and even depart materially from the course of its travel. Obviously, this action interferes with the smooth operation

of the multigraph, causing faulty printing and damage to the ribbon.

In order to overcome the above difficulties, I have designed the novel attachment in two companion units 15. Each of these is a strip of spring steel having a straight course for the most part, as indicated in Fig. 3, and being deflected at both ends as indicated at 15a. One end is turned in with a hook 15b, while the other end is struck up with an arch 15c and continued with a doubled terminal 15d. Upon the center of the strip is mounted a slightly spaced tongue 16, and similar tongues 16a are mounted on the deflected portions of the strip, all the tongues opening toward one side of the strip. The tongues may be riveted to the strip as indicated at 16b or otherwise connected thereto; or they may be made integrally with the strip if convenient.

As indicated in Fig. 1, the units 15 are designed to be arranged at opposite sides of the ink-ribbon 14 and positioned vertically. In order that the units may mate, the arched portions 15c thereof are both positioned at the top—or, they may be positioned at the bottom—and the tongues 16 are designed to have their openings on the sides facing the ribbon.

In applying the novel guiding attachment to the form 12, the units 15 thereof are first hooked on the lower stay rod 13 as clearly shown in Fig. 2 and drawn up and over the form to closely engage the periphery thereof, and enable the arches 15c to be sprung over the upper stay rod 13, the fingers using the terminal 15d as a hold for the manipulation of the units. The tension of the latter as well as the calculated length thereof will be such as to effect a snug and permanent wrapping of the attachment upon the form. The lateral spacing of the form units will be such as to permit the ribbon to be laid with its side edges over the units 15 and freely inside the tongues 16 thereof. Thus, the latter, which are three in number and may even be more, will prevent the ribbon from working sidewise during its travel and retain the same in proper condition during the operation of the cylinder. It may be added that the firm connection of the

attachment with the form 12 renders the attachment virtually an integral part of the latter, so that the guiding units 15 and tongues 16 may be relied upon to hold the 5 same positions at all times.

It is obvious that the novel attachment is of utmost simplicity, and being normally in practically straight form—as suggested in Fig. 3—may be compactly packed, stored or 10 mailed. Also, it is very easy to remove the attachment from the cylinder when the ribbon is to be changed, it only being necessary to snap the arch 15c off the corresponding stay rod 13 by drawing on the terminals 15d. 15 Finally, it is easily seen that the attachment may be reversed relative to either of the stay rods 13, as either end may be applied to a selected stay rod without prejudice to the useful position of the attachment.

20 I claim:

1. A guide for multigraph-cylinder ribbons comprising a pair of laterally-spaced strips adapted to be wrapped over the type form of the cylinder and positioned opposite 25 the side edges of the ribbon, and guide elements carried by the strips to check the lateral deviation of the ribbon during its travel.

2. A guide for multigraph-cylinder ribbons comprising a pair of laterally-spaced strips adapted to be wrapped over the type 30 form of the cylinder and positioned to receive over them the side edges of the ribbon, and guide elements carried by the strips to check the lateral deviation of the ribbon during its travel.

3. A guide for multigraph-cylinder ribbons comprising a pair of laterally-spaced strips adapted to be wrapped over the type 40 form of the cylinder and positioned to receive over them the side edges of the ribbon, and guide elements carried by the strips to check the lateral and radial deviation of the ribbon during its circular travel.

4. The structure of claim 2, said guide elements comprising tongues erected at the outer portions of the strips and extending immediately over the side edges of the ribbon to dispose the latter freely between the 45 tongues and the strips.

5. The combination with a multigraph cylinder having transverse stay-rods and a type form; of a guide for the cylinder ribbon comprising a pair of laterally-spaced strips adapted to be wrapped over the type form 55 and positioned opposite the side edges of the ribbon, elements carried by the strips to check the ribbon from lateral deviation, and terminals carried by the strips and engageable 60 with the stay-rods to hold the strips fast to the type form.

6. The structure of claim 5, one of said terminals being a hook and the other an arch.

7. The structure of claim 5, the strips being 65 of spring metal and tensioned snugly

to the type form periphery when the terminals engage the stay-rods.

8. The combination with a multigraph cylinder having transverse stay-rods and a type form; of a guide for the cylinder ribbon comprising a pair of laterally-spaced strips adapted to be wrapped over the type form 70 and positioned opposite the side edges of the ribbon, elements carried by the strips to check the ribbon from lateral deviation, terminals carried by the strips and engageable with the stay-rods to hold the strips fast to the type form, one of said terminals being a hook and the other an arch, and an extension from the latter to serve as a finger hold. 75

9. The combination with a multigraph cylinder having transverse stay-rods and a type form; of a guide for the cylinder ribbon comprising a pair of laterally-spaced strips adapted to be wrapped over the type form 80 and positioned opposite the side edges of the ribbon, elements carried by the strips to check the ribbon from lateral deviation, terminals carried by the strips and engageable with the stay-rods to hold the strips fast to the type form, one of said terminals being a hook and the other an arch, and an extension from the latter to serve as a finger hold, and said extension being doubled back on itself to give it body and stiffness. 85

10. A guide for multigraph-cylinder ribbons comprising a pair of laterally-spaced straight spring-strips, these being flexible to fit the periphery of the cylinder type form 90 at positions opposite the side edges of the ribbon, and inwardly opening guide elements carried by the strips to freely receive said side edges and check the lateral deviation of the ribbon during its travel. 95

11. The combination with a multigraph cylinder having transverse stay-rods and a type form; of a guide for the cylinder ribbon comprising a pair of laterally-spaced straight spring-strips, these being flexible to fit the periphery of the cylinder type form 100 at positions opposite the side edges of the ribbon, inwardly-deflected extensions of the strips, terminals carried by the free ends of the extensions and engageable with the stay-rods to hold the strips fast to the type form, and inwardly opening guide elements carried by the strips and extensions to freely receive said side edges and check the lateral deviation of the ribbon during its travel. 105

In testimony whereof I affix my signature.

LLOYD A. TUPPER.
